UNITED STATES PATENT OFFICE

120,508

DESIGN FOR A DRAPERY FABRIC

Harry Josephson, New York, N. Y.

Application March 8, 1940, Serial No. 90,760

Term of patent 3½ years

To all whom it may concern:

Be it known that I, Harry Josephson, a citizen of the United States, residing at New York, in the county of New York and State of New York, have invented a new, original, and ornamental Design for a Drapery Fabric, of which the following is a specification, reference being had to the accompanying drawing, forming part thereof.

The drawing is a plan view of a portion of a drapery fabric, showing my new design. The design consists of a series of stripes formed of multicolor yarns arranged as shown.

I claim:

The ornamental design for a drapery fabric, as shown and described.

HARRY JOSEPHSON.
